UNITED STATES PATENT OFFICE.

FRANK J. LASECKI, OF DETROIT, MICHIGAN.

CUSHION TOP.

Application filed February 8, 1919, Serial No. 275,703. Renewed November 1, 1923.

To all whom it may concern:

Be it known that I, FRANK J. LASECKI, a citizen of the United States of America, residing at Detroit, in the county of Wayne and State of Michigan, have invented certain new and useful Improvements in Cushion Tops, of which the following is a specification, reference being had therein to the accompanying drawings.

- 10 The invention relates to tops for cushions or seats and is adapted for use particularly in cushions or seats employing springs. One object of the invention is to provide a simple construction of cushion top which can be 65 cheaply manufactured and readily attached to a spring cushion or seat. Another object 15 of the invention is to provide a construction having means for yieldably maintaining the top or cover portion of the top taut, whereby 20 the same will present a neat appearance to the cushion or seat. Further objects reside in the arrangements and combinations of parts as more fully hereinafter set forth.

In the drawings:

- 25 Figure 1 is a bottom plan view of a cushion or seat with the cushion top applied; 80 Figure 2 is a bottom plan view of the cushion top itself; 85 Figure 3 is a transverse cross-section 90 through the cushion or seat with the top applied; Figure 4 is a perspective view of a portion thereof; 95 Figure 5 is a longitudinal sectional view 100 through a modified construction.

The cushion or seat is made up in any usual manner and in the present instance comprises the spring support 1, which includes the border frame 2 and the cross rods 3. Coil springs 4 are mounted upon the border frame and cross rods. 5 is padding upon the springs 4, and 6 is the cover having the depending skirt 7 extending around the springs and suitably secured to the border frame 2.

- 45 The cushion top comprises the top or cover portion 8 to the under side of which is stitched padding 9. This top or cover portion has the depending skirt portion 10 105 adapted to be located at the forward side of the cushion or seat and the depending side and rear skirt portions 11 and 12 respectively adapted to be located respectively at the sides and rear of the cushion or seat. The front skirt 10 extends from the top or 110 cover portion 8 beneath the border frame 2 and is provided with suitable clips 13 which extend up and around the cross rods 3 for holding the lower edge of the front skirt in place beneath the cushion or seat. 14 is a coil spring passing through a loop in the lower edge of the side and rear skirts 11 and 12 respectively, this spring terminating near the front skirt 10. The side and rear skirt portions 11 and 12 extend downwardly from the top or cover portion 8 a sufficient distance such that their lower edges will be slightly below the bottom of the padding 5 of the cushion or seat and this padding projects laterally outward a slight distance and the cover 6 forms with the depending skirt 7 a bead at the lower edge of the padding beneath which the coil spring 14 extends. This bead normally tends to retain the lower edge of the cushion top side and rear skirts from moving upwardly to disengage from the cushion or seat. The ends of the coil spring 14 are respectively secured to the front portion of the border frame 2 inwardly a slight distance from its ends so that the side skirt 70 portions 11 of the cushion top will be maintained adjacent to the side portions of the depending skirt 7 of the cushion or seat.

For maintaining the cushion top taut and substantially smooth from front to rear the series of springs 15 are provided at the rear side of the seat, these springs being preferably secured to the coil spring 14 at points in alignment with the rows of stitching for securing the padding 9 to the top or cover portion 8. The lower ends of these coil springs 15 have suitable clips 16 which extend down and around the rear portion of the border frame 2.

As shown in Figure 5, the lower edge of 95 the front skirt of the cushion top is positioned between the bars 17 and 18, one of which has the struck out lugs 19 passing through the edge of the skirt and the other bar and clinched thereover. Clips 20 are 100 rotatably secured to the bars 17 and 18 as by the rivets 21, these clips adapted to be moved up between adjacent cross connections 3 of the spring frame and then rotated to have their ends extend thereover, the 105 bodies of the clips being located between the cross connections.

From the above description it will be readily seen that I have provided a simple construction which can be easily applied 110

or removed from a spring cushion or seat. Furthermore, the construction is such that the top or cover portion of the cushion top will be maintained taut and substantially 5 smooth from front to rear irrespective of the condition of the padding in the cushion or seat. This construction can be applied to 10 cushions in which the covering and skirt are worn out and unsightly or in which the padding has become dislocated. Also this cushion top may be directly applied over the springs of cushions or seats instead of applying the usual cover with its depending skirt.

15 **What I claim as my invention is:**

1. In a cushion or seat, the combination with a spring support, springs mounted thereon and padding upon said springs, of a cushion top attachably secured thereto, 20 comprising a top portion, a depending front skirt extending from said top portion beneath said spring support and depending side and rear skirts, a coil spring extending around the lower edge of said side and rear 25 skirts, and a series of coil springs secured to said first-mentioned coil spring for maintaining the latter below the bottom of said padding.

2. In a cushion or seat, the combination 30 with a spring support and springs mounted thereon, of a cushion top secured thereto, comprising a cover portion, padding on the under side of said cover portion and secured thereto by transversely extending stitching, a 35 skirt between said cover portion and spring

support at one side of said springs and secured directly to said spring support, and a series of resilient members at the opposite side of said springs and secured to said cover portion in substantial alignment with said 40 stitching, adapted to yieldably maintain said cover portion taut.

3. In a cushion or seat, the combination with a spring support and springs mounted thereon, of a cushion top comprising a top portion, a depending skirt at one side of said springs and secured to said spring support, and a depending skirt at the opposite side of said springs, a flexible member extending around the lower edge of said last- 45 mentioned skirt, and a series of yieldable members secured to said lower edge and to said spring support for yieldably maintaining said top portion taut.

4. In a cushion or seat, the combination with a spring support and springs mounted thereon, of a slip-on cushion top secured thereto, comprising a top portion, a front skirt extending from said top portion into contact with said spring support, and a rear skirt terminating above said spring support, means for securing said front skirt to said spring support, and means for conforming said rear skirt to the contour of the cushion or seat and securing said rear skirt to said 50 spring support.

In testimony whereof I affix my signature.

FRANK J. LASECKI.
